UNITED STATES PATENT OFFICE.

WILLIAM G. BETZ, OF BUFFALO, NEW YORK, ASSIGNOR TO STRAUBE PIANO COMPANY,
OF HAMMOND, INDIANA, A CORPORATION OF INDIANA.

MUSIC-ROLL-CONTROLLING MECHANISM.

1,344,574.

Specification of Letters Patent. Patented June 22, 1920.

Application filed February 7, 1917. Serial No. 147,136.

To all whom it may concern:

Be it known that I, WILLIAM G. BETZ, a citizen of the United States, residing at Buffalo, in the county of Erie and State 5 of New York, have invented new and useful Improvements in Music-Roll-Controlling Mechanism, of which the following is a full, clear, concise, and exact description, reference being had to the accompanying 10 drawing, forming a part of this specification.

My invention relates to pneumatic musical instruments, and has to do more particularly with music-roll controlling mechanism.

One of the new features of my invention is the improved mechanism for alining the music-roll and the tracker-bar; that is, an improved method of lining up the music- 20 roll with the tracker-bar so that the perforations in the music-roll will register with the ports in the tracker-bar. There are various other features in my invention, but these will be more particularly pointed out 25 in the ensuing specification and claims.

Various means have been suggested for effecting a registration of the music-roll perforations and the tracker-bar ports. In my improved mechanism for doing this I prefer- 30 ably adjust an inner face of a head of the music-spool in definite relation to the ports of the tracker bar. I find that in the man- ufacture of music-spoons there is a slight variation in dimensions, but that the music- 35 sheets are practically of the same width and line up against the inner surface of the fixed head of the music-spool. I provide an alinement device which adjusts the music-spool so that the inner face of the fixed head 40 of the spool is in definite relation to the ports in the tracker-bar. The one edge of the music-roll, of course, engages the inner face of this fixed head of the music-spool. The perforations of the music-roll being 45 always cut in a certain relation to the edge of the music-roll, it will be apparent that, if the corresponding inner edge of the spool-head is in definite relation to the tracker-bar ports, then the perforations in the music- 50 sheet must register with the tracker-bar ports.

For a better understanding of my invention, reference is to be had to the accompanying drawings, in which—

55 Figure 1 is a front view of the preferred

form of music-roll controlling-mechanism of my invention;

Fig. 2 is a rear elevation of the same;

Figs. 3 and 4 are left and right end views, respectively, of the mechanism of Fig. 1;

Fig. 5 is a partial sectional view through the pneumatics or bellows for controlling the alinement mechanism;

Fig. 6 is a sectional view along the line 6—6 of Fig. 5, showing the alinement lock- 65 ing-mechanism;

Fig. 7 is a sectional view along the line 7—7 of Fig. 1, showing the music-spool and stop-arm;

Fig. 8 is a sectional view along the line 8—8 of Fig. 2, showing the valves for controlling the stop pneumatic;

Fig. 9 is a sectional view along the line 9 of Fig. 1, showing the shifting-mechanism for the upper shaft and the brake 75 therefor; and

Fig. 10 is a sectional view along the line 10 of Fig. 1, showing the shifting-mechanism for the lower shaft and the brake therefor.

Referring now more in general to the preferred form of my invention as illustrated in the drawings, it comprises a frame A supporting a music-spool B, a take-up spool C, and spool-operating mechanism D. 85 A music-spool shifting pneumatic E is also provided and is adapted when operated to laterally shift the shafts of the two music-spoons toward the left, in order to line up the music-sheet and the tracker-bar. A 90 locking pneumatic F is also provided and is adapted to stop the shifting operation of the pneumatic E when the music-spool has been shifted laterally far enough to line up with the tracker-bar H.

Referring now more particularly to the preferred construction of my invention as illustrated, I provide a frame A comprising a base 1 preferably of wood and having attached thereto metal sides 2 and 3, to 100 which are fastened a bottom back 4 and a top back 5, the back pieces being preferably of wood. The bottom back piece 4 is preferably a flat piece, while the top back 5 is rounded out, as shown by the dotted lines 105 in Fig. 4.

In order to accommodate the frame to different kinds of pianos, I provide adjustable stud means which are secured to the base-board 11, as shown in Fig. 1; that is, 110

four threaded studs 12 are secured to the base-board 11 and project upwardly through the base 1 of the frame. Nuts 13 are provided for clamping the base 1 and holding it in the proper position.

In order to support the music-spool B, I provide at the left end of the spool a spring-pressed or yielding shaft member 14, the operation of which is well understood. 10 For supporting the right end of the music-spool B a driven shaft 15 is provided (see Figs. 1 and 9) having a head adapted to fit within the sockets of the spool-head. This shaft 15 has its bearings in the frame-plate 3 and the end frame-plate 16, the shaft being laterally movable in a manner as will hereinafter be more particularly described.

The take-up spool C is supported by a yielding shaft at its left end and a driving-shaft 18 at its right end, this shaft 18 being supported in bearings in the plates 3 and 16, as shown in Figs. 1 and 10. This shaft 18 is also laterally movable for shifting the take-up spool in a manner as will be herein-25 after more particularly described.

The spool-operating mechanism D, which is more particularly illustrated in Figs. 1, 2, 9 and 10, is supported by a novel frame arrangement consisting of the plates 3 and 16, 30 which are securely held together by means of screws 19-20, sleeves 21-22, and sleeves 23-24, shown in cross section in Fig. 2. These sleeves not only serve to hold the frame together, but also act as bearings for 35 the vertically-disposed shafts 25-26, which shafts have their ends entering into bearings provided in these sleeves, as shown more particularly in cross section in Fig. 2. The shaft 25 carries the gear-shift and brake-40 mechanism, while the shaft 26 carries the shifting-arms 27-28 for shifting the spool-shafts 15 and 18. The arms 27-28 press against the ends of the shafts 15 and 18, which are pressed toward the right by the 45 action of the spring-pressed shafts at the left end of the spools. Thus, as the shaft 26 is rotated toward the left or toward the right, the spool-shafts 15 and 18 are moved laterally correspondingly. The method of 50 operating the shaft 26 will be more particularly referred to later on.

As to the gear-shifting mechanism controlled by the shaft 25, it will be noted that the main driving-shaft 29 is provided with a 55 driving-gear 30, which is connected to the main motor of the musical instrument being played. This shaft 29 is supported in bearings in the plates 3 and 16 and carries a gear 31 connected by a chain 32 to a gear 33 fixed to the music-spool shaft 15. Also on the main shaft 29 is a slideable pinion 34, which is moved laterally on the shaft 29 by means of the arm 35 fastened to the shifting-shaft 25. At the bottom end of the 60 shaft 25 is a lever 36, which is connected by 65

a rod 37 to the usual shifting-lever at the front of the piano. The main driving-pinion 34 carries a pin 39, which is adapted to engage a pin 40 carried by the gear 31; that is, when the main driving-pinion 34 is shifted toward the right, the pins 39 and 40 co-operate, the pin 39 thus rotating the gear 31, whereby the music-spool shaft 15 is rotated. This is used for rewinding the music-roll. When the main driving-gear 34 is shifted toward the left, it engages a gear 41, which gear is fixed to the take-up spool-shaft 18. Thus, when the gears 34 and 41 are in mesh, the take-up spool C is rotated to operate the music-sheet for playing.

In order to prevent slack in the music-sheet during the playing or rewind operation thereof, brakes are provided to operate upon the idle one of the spools B or C; that is, when the music is being played the take-up 85 spool C is drawing the sheet of music toward it and the music-spool B is idle, and to prevent the spool B from running free and allowing slack in the sheet-music, a brake is applied to a drum 42 carried by the shaft 15 90 (as shown in Fig. 9). With the shifting-lever 36 in its rewind position, as shown in Figs. 9 and 10, the main driving-gear 34 is operating upon the large chain-gear 31, and at this time the leather brake-shoe 43 upon 95 the drum 42 is open, because the pin 45 carried by the shifting-shaft 25 is pressing upon the spring 44 and maintaining the brake 42-43 inoperative. However, at this time the brake upon the take-up spool C is 100 effective as shown in Fig. 10. This brake also consists of a leather brake-shoe 46 adapted to press upon the hub or drum 47 of the gear 41. With the shifting-lever 36 in the right-hand or take-up position, as 105 shown in Fig. 10, the music-spool B is being driven, and therefore the brake 46 is applied to the take-up spool C in order to prevent slack of the music-sheet. This 110 brake 46 is carried upon the spring 47, which spring co-operates with the pin 48 carried by the shifting-shaft 25.

In the operation of the shifting and braking-mechanism, when the shifting-lever 36 is to the right, the music-spool B is being driven to rewind the music-sheet, at which time the driving pins 39-40 on the main driving-gear 34 are in engagement and the brake 46-47 upon the take-up spool C is effective. However, when the shifting-lever 36 is in its left-hand or playing position, the main driving-pinion 34 and the large gear 41 are in mesh, and the take-up spool C is being driven. At this time the brake upon the take-up spool C is not effective, because the pin 48 (see Fig. 10) is engaging the spring 47 and the lower brake-shoe is disengaged. At this time, however, the pin 45 upon the upper brake has moved to the right away from the spring 44 and allowed 130

the brake 42—43 upon the upper spool to become effective.

As already referred to, due to the spring-pressed shafts 14 and 17 at the left end of the music-spool B and C, these spools are pressed toward the right, so that the side bearings of the shafts 15 and 18 normally engage the inner faces of the side plate 3, as shown in Fig. 1. It will also be remembered that the ends of the shafts 15 and 18 are rounded and engage the inner faces of the shifting-plates 27—28, as shown in Figs. 1, 9 and 10. Therefore, if the spool-shifting shaft 26 is rotated, the plates 27—28 simultaneously press against the ends of the shafts 15 and 18 and move the spools B and C toward the left against the tension of the spring-pressed shafts 14 and 17. It will thus be apparent that, when the spools are shifted to line up the music-sheet with the ports in the tracker-bar H, both spools are moved simultaneously, resulting in a lateral shifting of the whole music-sheet and spools.

One of the reasons that the regular commercial music-sheet and the tracker-bar do not always come into proper alinement is that in the manufacture of music-spoles such as are here employed, there is a variation in dimensions of the head 49. That is, there is a variation in the distance between the inner face 50 of the head and the stop face 51. It will be apparent that, although the shaft 15 may be permanently fixed, if this dimension just referred to varies then the edge 52 of the music-sheet will not always come in the same relation to the tracker-bar H. In the manufacture of the music-roll the perforations are made in definite relation to the edge of the sheet. In order to care for slight variations in the width of the sheet, which may be caused in manufacture or by atmospheric or other changes, the left head 53 of the music-spool is usually made laterally movable. That is, although the right head 49 is fixed to the spool core, the left head 53 has a slight lateral movement, so that it will always tend to keep the inner faces of the two heads against the edges of the sheet while the spool is held between the shafts.

In order to effect a proper alinement of the music-sheet and the tracker-bar, I preferably provide alining mechanism controlled by the inner face 50 of the fixed head 49 of the spool. As already explained, the dimensions of the fixed head 49 may vary, and therefore in placing the spool in the holder the inner face 50 will not always normally come in a certain definite relation to the tracker-bar H. Therefore, I preferably shift the spool B toward the left until the inner face 50 of the fixed head comes into definite relation to the tracker-bar, and the spool is then held in this position while the piece is being played.

In order to take care of the greatest variation in spool heads, I preferably construct the shaft 15 so that with the greatest thickness of spool heads (which I have found do not vary more than $\frac{1}{8}$ of an inch) the inner face 50 of the fixed head assumes a position slightly to the right of its playing position.

The spool-shifting or alinement mechanism already referred to consists of the shifting-pneumatic E, which by its operation shifts the music into proper alinement with the tracker-bar. The stop-pneumatic F then operates so that the shifting-pneumatic will hold the music in its proper position. For this purpose I provide a shaft 152 (see Fig. 2) carrying a felt-capped stud 153 at one end, which is adapted to be engaged by the arm 54 carried by the pneumatic E when said pneumatic is closed. This shaft 152 is carried in an arm 55 and passes through a V-shaped orifice 56 in this arm 55, as shown in Fig. 6. The other end of the shaft 152 is pivotally connected to a lever 57 securely attached to the shaft 26. It will thus be apparent that when the pneumatic E is closing, the arm 54 engages the stud 153 of the shaft 152 and presses it toward the left (Fig. 2). This moves the lever 57 and thus presses the plates 27—28 (see Figs. 9 and 10) against the shafts 15—18 and moves the spools B and C toward the left (see Fig. 1). However, before this shifting of the spools occurs, a stop-arm 59 (Figs. 1 and 7) is rotated downwardly into operative relation with the inner face of the fixed head of the music-spool. This operative position is shown by the dotted lines in Figs. 1 and 7. The stop-arm 59 is rotatable relative to a shaft 60, but is not laterally movable relative to this shaft. For this purpose the hub 62, which carries the arm 59, is slotted at 62 and embraces a pin 63 carried by the shaft. Thus, as the shaft 60 is rotated in a clockwise direction (looking at Fig. 7) the arm 59 moves downwardly until it engages the music on the spool B. As is understood, these music-spoles come in various sizes, according to the composition, and in order to take care of this variation the arm 59 is provided with this rotary play. The shaft 60 has a definite angular rotation, so that it will be seen that if a roll larger than the one illustrated in Fig. 7 were used, the shaft 60 in rotating would allow the arm 59 to come in contact with the music on the roll, and any further rotation of the shaft 60 would simply cause the pin 63 to move away from the end of the slot 62 and allow the arm 59 to remain lightly in engagement with the music-sheet.

The rotary operation of the shaft 60 is brought about by the link connection 64, which is pivotally connected to an arm 65 on the shaft 60 and is also pivotally con-

neeted at its lower end 66 to an arm 67, secured to the pneumatic E. Thus, when the pneumatic E is closed, the arm 67 moves downwardly, carrying the link 64 with it and thus rotating the shaft 60 and causing the stop-arm 59 to come into operative relation with the music-spool B.

Thus, it will be seen that in the initial closing movement of the pneumatic E, the 10 stop-arm 59 is first brought into operative relation with the music-spool B, after which the continued closing movement of the pneumatic E effects engagement between the arm 54 and the tip 153 of the shaft 152, thus 15 shifting the two spools, the shifting movement continuing until the inner face 50 of the spool head 49 engages this stop-arm 59. As already referred to, the heads of the 20 music-spools vary in dimensions and therefore the shifting movement will vary, because this movement must be such as to bring the inner face of the spool head 49 in proper relation to the tracker-bar. The 25 control of the shifting movement is in the stop-pneumatic F.

In order to stop the shifting or alinement operation of the pneumatic E, a controlling valve J for the stop-pneumatic F is provided upon the stop-arm shaft 60. This 30 valve is operated by a lateral movement of the shaft 60, brought about by engagement between the stop-arm 59 and the spool head. This valve comprises a stationary hub 69 secured to the frame and acting as a bearing 35 at the left end of the shaft 60, as shown in Fig. 1. This hub 69 has a port-hole 70 extending therethrough, as shown in Figs. 1, 2 and 8, the port opening being upon the lateral face of the hub 69, which is engaged 40 by the collar 71. This port-hole 70 is connected, by means of a flexible tube 72, to a valve 85 controlling the stop-pneumatic F. The purpose of the stop-valve J is to connect the tube 72—and thus the valve-chamber 45 83—with the atmosphere. This is accomplished by moving the shaft 60 toward the left against the tension of the spring 95, thus moving the collar 71 laterally away from the hub 69 and exposing the opening to 50 the atmosphere. That is, when the spool head engages the stop-arm 59 a continued lateral movement of the stop-arm and the shaft 60 causes the collar 71 to move away from the hub 69 and thus open the port- 55 hole 70 and expose this port to the atmosphere. As soon as the valve J is opened the stop-pneumatic F operates to prevent further lateral movement of the music- 60 spools. This will be more particularly described later.

Both pneumatics E and F are operated through a tube 73 connecting the main vacuum chamber of the piano with the local vacuum chamber 74 in the block 75, shown 65 in Fig. 5. This vacuum chamber 74 is con-

nected by means of a duct 76 with the alinement pneumatic E. This chamber 74 is also connected with the stop pneumatic F by means of a duct 77, shown at the bottom of the block 75. The duct 77 may be connected 70 with the vacuum chamber 74 or with the atmosphere through the duct 78, according to the position of the valve-mechanism shown within the block 75. This valve-mechanism preferably comprises a sheet metal plate 75 having spring arms 79 adapted to engage a double pointed shaft for supporting the valve-arm 80. This valve-arm 80 carries a buffer 81 for coöperating with the pouch 82, which is preferably of leather and glued 80 over the chamber 83, which chamber is connected by means of the tube 72 to the valve J already referred to. The chamber 83 is also connected by means of a duct 84 with the auxiliary vacuum chamber 74. The 85 valve-arm 80 also carries a double leather-faced valve 85, which is adapted to seat against the plate 86 or the face 87, according to the position of the arm 80. Thus, the duct 77 connects the stop-pneumatic F with 90 the vacuum chamber 74 or atmosphere, according to the position of the valve 85. The opening 78 leading from the valve 85 to the atmosphere is covered by means of a cloth screen 186 to prevent the entrance of dirt. 95 So long as the valve J is closed, the degree of vacuum on each side of the pouch 82—that is, in the chambers 83 and 74—is the same, so that the valve 85 remains in engagement with the seat of plate 86. However, if the duct 72 is exposed to the atmosphere, the vacuum in the chamber 83 drops, that is, there is an increase in absolute pressure in chamber 83. There is thus a difference in pressure on opposite sides of the 100 pouch 82, resulting in a movement of the valve-lever 80 to the right, closing the atmosphere duct 78 and connecting the stop-pneumatic F with the chamber 74, through the duct 77, resulting in the operation of the 105 pneumatic F. This lifts the rod 88, which is connected to a cam 89 pivoted at 90, causing the operative end of the cam 89 to move downwardly against the shaft 152, locking it against the side of the V-shaped orifice 56 110 and thereby preventing further lateral movement of the shaft 152. However, when the locking-cam 89 operates, there is a slight retractive movement of the pneumatic E to relieve the otherwise frictional engagement 115 between the spool-head and the stop-arm. This is brought about by a sudden increase in absolute pressure, or in other words drop in the vacuum in the chamber 74, due to the movement of the valve 85 and the rush of 120 air from the pneumatic F into the chamber 74 and the pneumatic E and also the exposure of the duct 72 to the atmosphere at the valve J permitting air to enter chamber 74 through duct 84. Therefore the pneu- 125 130

matic E retracts sufficiently to permit a small movement of the shaft 152 toward the left, Fig. 5, which movement continues until the valve J closes again. This valve J, it is 5 to be understood, had opened only slightly, $\frac{1}{64}$ to $\frac{3}{32}$ of an inch, as I have found. The retractive or expanding movement of the pneumatic E until valve J is again closed is thus very slight. As soon as the valve J 10 closes again the duct 72 is, of course, closed, so that the vacuum in the chambers 74 and 83 immediately balances and the valve seat 86 again closes, disconnecting the vacuum chamber 74 from the stop-pneumatic F. 15 However, before the stop-pneumatic F has had time to release the stop-cam 89, the pneumatic E has started to close again, but its closing movement is practically *nil*, being limited by the tip 153 of the shaft 152, 20 because locking-cam 89 is in a position to prevent a movement of the shaft 152 toward the right. This slight retractive movement of the pneumatic E just referred to is sufficient to allow the music-spool B to slightly 25 disengage from the stop-arm 59, so that there is no frictional engagement between the arm 59 and the face of the spool-head 49 during the playing operation. It will be apparent that if the stop-arm 59 were permitted to ride against the side of the spool B during the playing operation, a retarding effect upon the spool B would be produced, and it is to avoid this retarding or frictional 30 engagement between the arm 59 and the spool B that the stop-pneumatic F and associated mechanism are provided.

On account of this slight retractive movement of the music-spools, I preferably adjust the mechanism so that upon the initial 40 closure of the shifting or alinement pneumatic E the spools B and C will carry the music-sheet 52 slightly to the left of the tracker-bar ports; that is, the music-sheet is moved to the left so that the perforations 45 therein are slightly to the left of the ports. The retractive movement of the spools to relieve the frictional engagement between the stop-arm 59 and the spool-head 49 then carries the music-sheet back so that the perforations 50 and the ports are in proper alinement.

Operation.

Having described in detail the operation 55 of the various elements entering into the preferred form of my invention as shown herein, I will now describe the operation of the device as a whole.

The operator first inserts a music-spool B 60 between the shafts 14—15, said spool being pressed toward the right, due to the yielding shaft 14. As already described, the adjustment of the mechanism is such that the inner face 50 of the spool-head 49 is normally to the right of the stop-arm 59, the

distance varying according to the size of the spool-head 49. The music is now secured to the take-up spool C in the usual manner. The operator, by means of the usual lever at the front of the piano, now shifts the 70 gear-shift lever 36 to the left, thereby rotating the shaft 25 and causing the arm 35 to move the pinion 34 into mesh with the gear 41. This operation of the shaft 25 (see Figs. 9 and 10) causes the brake-shoe 43 to engage the drum 42 of the upper shaft, while the brake-shoe 46 on the lower shaft is moved free of the drum 47. The operator now starts to pedal in the usual manner, thereby creating a vacuum in the main 75 vacuum chamber of the piano, causing the motor to drive the main shaft 29 of the mechanism. The shaft 29 is rotated in a clockwise direction, as indicated by the arrow on the gear 30 in Fig. 4.

As soon as the vacuum is created in the main vacuum chamber of the piano, this also produces a vacuum in the auxiliary chamber 74 in the block 75, because of the connection 73 (Fig. 6) from the chamber 74 to 80 the main vacuum chamber. The shifting-pneumatic E is, therefore, immediately closed, and upon the initial closing movement thereof the stop-arm 59 is first brought into the path of the music-spool B. This is 85 brought about by the operation of the arm 67 connected to the pneumatic E, which arm is connected by the link 64 to the stop-arm shaft 60, the operation of these parts causing a rotation of the shaft 60 and bringing the 90 arm 59 downwardly into the path of the spool-head 49. The continued closing movement of the pneumatic E now causes the arm 54 carried thereby to engage the tip 153 of the shaft 152 (see Fig. 2) moving said shaft 105 152, which, being connected to the shifting-shaft 26, causes a rotation of this shaft, whereby the arms 27—28 carried thereby press against the ends of the shafts 15—18, causing a lateral shift of the music-spools B 110 and C toward the left. This movement of the spools continues until the inner face of the spool-head 49 engages the stop-arm 59, whereupon a slight continuing movement of the spool B causes the arm 59 and the 115 shaft 60 to move toward the left. This causes an operation of the valve J by a separation between the collar 71 and the hub 69. This opens said valve J and exposes the port 70 therein to the atmosphere. The 120 valve J is connected by means of the tube 72 to the pouch-chamber 83, thereby reducing the vacuum in the chamber 83, and, there being thus an unequal pressure upon the opposite sides of the pouch 82, the valve 125 buffer 81 engaged thereby is moved toward the right, opening the valve seat 85—86 and closing the valve seat 85—87. The stop-pneumatic F is therefore connected with the auxiliary vacuum chamber 74, and this 130

pneumatic immediately closes, operating the stop-cam 89 and locking the shaft 152 against further movement toward the right, Fig. 5, thus preventing a further closing operation of the shifting-pneumatic E.

At this point in the operation of the mechanism, we have the inner face of the spool-head 49 pressing against the stop-arm 59, which is under tension of the spring 95 at the end of the shaft 60. It will be apparent that, if the mechanism were operated in this state, the frictional engagement between the stop-arm 59 and the spool-head 49 would interfere with the free operation thereof. To relieve this frictional engagement during the playing operation of the mechanism, I permit a slight retractive movement of the spool B, sufficient to relieve the spool-head 49 from engagement with the stop-arm 59. This is brought about in the following manner: At the time the valve J was operated to effect operation of the stop-pneumatic F, there was a momentary increase in absolute pressure or drop in vacuum in the auxiliary chamber 74, due to the exposure of the valve J to the atmosphere and the movement of the valve 85 from left to right. This momentary increase in absolute pressure or drop in vacuum in the chamber 74 permits a slight retractive movement of the pneumatic E, which movement in practice is far enough to permit the valve J to again close. This closing, of course, immediately decreases the absolute pressure or increases the vacuum in the chamber 74, but before this vacuum has time to again permit collapse of the pneumatic E, said pneumatic has a further slight retractive movement sufficient to disengage the spool-head 49 from the stop-arm 59. By this time the pneumatic E is again attempting to close, but, due to the effect of the locking-cam 89 upon the shaft 152, further closing operation of this pneumatic is prevented and the continued tendency to close simply causes it to press against the end of the shaft 152 and effect an increased holding of the locking-cam 89.

It will be noted that in the adjusting operation of the music-spools they were first shifted laterally toward the left and then slightly retracted to disengage the spool-head 49 and the stop-arm 59. In order to cause alinement of the spool and tracker-bar after the final retractive movement of the spools, the mechanism is so adjusted that upon the initial lateral shift of the spools the music-sheet is moved toward the left so that the perforations are slightly beyond the tracker-bar ports. When the spools retract, the perforations and the ports are in proper alinement.

The mechanism remains in this adjusted position as long as the player is being operated; that is, as long as the pedals are be-

ing operated and a vacuum in the main chamber of the player maintained, the pneumatic E is kept closed. Therefore, the spools remain in their adjusted position during the playing operation.

At the time the pneumatic E was last closed to effect the final holding operation, it will be recalled that the valve J had been closed. As already stated, this permitted a balance of pressure in the chambers 74-83, due to the connection extending through the duct 84. Therefore, the valve 85 will again seat upon the plate 86. This disconnects the stop-pneumatic F from the vacuum chamber 74, but this pneumatic does not retract, because at this time the pneumatic E is pressing against the end of the shaft 152 and maintaining the locking-cam 89 effective. In this way the pneumatic E only is held operated during playing, and the stop-pneumatic F is disconnected. Thus a saving of power is effected, because if both pneumatics were connected during the playing operation more power would be necessary to maintain the proper vacuum.

When the operator stops playing, the vacuum in the main chamber of the piano of course drops and the pneumatic E retracts, allowing the parts to restore to normal. The operator now shifts the gear-shift lever 36 in the usual manner and thereby connects the driving-shaft 29 through the chain with the spool B to rewind the music-sheet.

I claim—

1. An alinement device of the character described comprising a music spool and tracker bar, spool operated means for definitely alining the music-spool and the tracker-bar and maintaining such definite alinement during playing, and means for automatically shifting the spool longitudinally for operating said alining means.

2. A music-roll alinement device of the character described comprising spool-shifting mechanism, and spool controlled means for operating said mechanism to effect and maintain a predetermined alinement of the music-spool and tracker-bar.

3. A music-roll alinement device of the character described comprising spool-shifting mechanism, and automatically operated controlling pneumatics for operating said mechanism to shift the spool into a predetermined relation to the tracker-bar and maintaining the spool in such relation during playing.

4. A music-roll alinement device of the character described comprising a tracker-bar and music-spool, shifting-mechanism for effecting a predetermined alinement of the spool and the tracker-bar, a shifting-pneumatic for operating said mechanism to shift the spool and bar into said predetermined alinement, a stop-pneumatic for limiting the

shifting operation of the shifting-mechanism, and automatic means for controlling the pneumatics.

5. A music-roll alinement device of the character described comprising a tracker-bar and music-spool, pneumatically-operated mechanism for effecting a lateral relative shift to the tracker-bar and spool, a stop operative upon a predetermined alinement of 10 the tracker bar and spool when being shifted by said mechanism, and a stop-pneumatic controlled by said stop when so operated.

6. Music-roll operating-mechanism comprising a frame, a laterally-movable spool-shaft supported in said frame, means for 15 limiting the lateral movement of the shaft in one direction, a music-spool, yielding means including said spool tending to hold the shaft in the limit of said direction, a 20 swinging arm pressing against an end of the shaft, pneumatically-controlled means for operating said arm to move said shaft laterally against said yielding means, and spool-controlled means for controlling said pneumatically controlled means.

7. A music-spool alinement device of the character described comprising a tracker-bar, music and take-up spools, a shifting-pneumatic for shifting the spools laterally 30 relatively to the tracker-bar, a movable stop-arm engaged by an inner face of the spool head for limiting the lateral movement of the spools, and means controlled by the stop-arm for effecting such limiting movement.

35 8. A music-spool alinement device of the character described comprising a tracker-bar, music and take-up spools, pneumatically-controlled mechanism for shifting the spools relatively to the tracker-bar, means 40 for operating said mechanism upon initial creation of a vacuum in the main chamber of the piano, a movable stop-arm adapted to be engaged by an inner face of a spool head when the spools are shifted, and means controlled by the stop-arm when so engaged to 45 limit the lateral movement of the spools.

9. A music-spool alinement device of the character described comprising a tracker-bar, laterally-movable music and take-up 50 spools, a movable stop-arm, a shifting-pneumatic connected to the main vacuum chamber and operated when the vacuum is initially created, mechanism responsive to said pneumatic to first move the arm into the path of a spool head and thereafter move the spools laterally, whereby the inner face of a spool head engages and moves said stop-arm, and a stop-pneumatic responsive to the 55 stop-arm to limit the shifting operation of the shifting-pneumatic.

60 10. A music-spool alinement device of the character described comprising a tracker-bar, laterally-movable music and take-up

spools, a movable stop-arm, mechanism for moving the arm into the path of a spool head and thereafter moving the spools laterally whereby the inner face of a spool head engages and moves the stop-arm to limit said movement of the spools, and means for thereafter disengaging the stop-arm and 70 spool.

11. A music-roll alinement device of the character described comprising a tracker-bar and music-spool, shifting-mechanism for effecting a predetermined alinement of the 75 spool and the tracker-bar, a shifting-pneumatic for operating said mechanism, a stop-pneumatic for limiting the operation of the shifting-mechanism, and a spool-operated stop for controlling said pneumatics. 80

12. A music-spool alinement device of the character described comprising a tracker-bar, a shifting-pneumatic for shifting the spools laterally relatively to the tracker-bar, a spool actuated stop-arm, and means controlled by the stop-arm for limiting the operation of the shifting-pneumatic. 85

13. A music-spool alinement device of the character described comprising a tracker-bar, music and take-up spools, a shifting-pneumatic initially operative for shifting the spools laterally relatively to the tracker-bar, a movable stop-arm engaged by an element movable with a spool upon a predetermined alinement of that spool and tracker-bar and means controlled by the stop-arm for limiting the operation of the shifting-pneumatic. 90

14. A music-spool alinement device of the character described comprising a tracker-bar, music and take-up spools, a shifting-pneumatic for shifting said spools laterally relatively to the tracker-bar, a spool controlled stop-arm, and means controlled by the stop-arm for limiting the shifting-motion of the spools. 100

15. A music-spool alinement device of the character described comprising a tracker-bar, music and take-up spools, a shifting-pneumatic for shifting said spools laterally 110 relatively to the tracker-bar, a spool-controlled stop-arm, means controlled by the stop-arm for limiting the shifting-motion of the spools, and means for disengaging the stop-arm and spool. 115

16. A music alinement device of the character described comprising a music spool support and tracker bar, mechanism for relatively shifting the spool support and tracker bar to effect a predetermined alinement thereof, and control means for the shifting mechanism operable by an inner face of the music spool head. 120

In witness whereof, I have hereunto subscribed my name.

WILLIAM G. BETZ.
